UNITED STATES PATENT OFFICE

JOHN P. V. HEINMULLER, OF NEW YORK, N. Y., ASSIGNOR TO A. WITTNauer CO., OF NEW YORK, N. Y., A CORPORATION OF NEW YORK

DESIGN FOR A WATCH DIAL OR SIMILAR ARTICLE

Application filed September 27, 1930. Serial No. 37,082. Term of patent 3½ years.

To all whom it may concern:

Be it known that I, JOHN P. V. HEINMULLER, a citizen of the United States of America, and a resident of the borough of Manhattan, city, county and State of New York, have invented a new, original, and ornamental Design for a Watch Dial or Similar Article, of which the following description, in connection with the accompanying drawing, is a specification.

The figure is a plan view of a watch dial or similar article showing my new design.

I claim:

The ornamental design for a watch dial or similar article, substantially as shown.

JOHN P. V. HEINMULLER.
